SUCTION NOZZLE

Gosta Dahl, Stockholm, Sweden, assignor to
Electrolux Corporation, Dover, Del., a corpora-
tion of Delaware

Application July 7, 1937, Serial No. 152,291
In Germany July 18, 1936

2 Claims. (Cl. 285—91)

This invention relates to a suction nozzle for vacuum cleaners or the like and more particularly to a nozzle which is adjustable in all directions in accordance with the surface to be cleaned.

5 An object of the invention is to provide a suction nozzle which is readily adjustable for the purpose above indicated.

Another object is to provide a nozzle having a ball and socket connection to the suction conduit 10 and which is movable through a substantial angle.

Another object is to provide a ball and socket connection for a suction nozzle in which the arc of contact between the ball and socket is reduced to a minimum.

15 Another object is to provide a device of the above type which can be readily assembled and disassembled.

Various other objects and advantages will be apparent as the nature of the invention is more 20 fully disclosed.

Although the novel features which are believed to be characteristic of this invention are pointed out more particularly in the claims appended hereto, the invention will be better understood by referring to the following description taken in connection with the accompanying drawing in which certain embodiments thereof have been set forth for purposes of illustration.

In the drawing:

30 Fig. 1 is a plan view of a suction nozzle and conduit constructed in accordance with the present invention showing the nozzle applied to a surface to be cleaned;

Fig. 2 is a vertical section through the nozzle and the adjacent part of the suction conduit showing the ball and socket connection.

Fig. 3 is a transverse section taken along the line 3—3 of Fig. 2;

Fig. 4 is a detail view showing one means for connecting the guide member to the supporting pin;

Fig. 5 is a longitudinal section similar to Fig. 2 showing a different embodiment of the invention; and

45 Fig. 6 is a transverse section taken on the line 6—6 of Fig. 5.

Referring to the drawing more in detail, Fig. 1 shows a suction nozzle 10 of general triangular shape which is mounted by means to be described, on a connector 11, adapted to be attached to a handle 12 which forms a part of the suction conduit.

The triangular suction nozzle 10 is shown as applied to a surface bounded by a frame 13 and illustrates the manner in which the suction nozzle

enters the corner of the frame for cleaning purposes. It is to be understood that the edges of the suction nozzle may be provided with a suitable brush 23 as shown in Fig. 2 to facilitate cleaning.

The suction nozzle 10 is attached to the connector 11 by means of a ball and socket joint which comprises a ball 14 formed on the connector 11 and a socket 15 formed in the housing of the suction nozzle 10.

The ball 14 and socket 15 are so arranged that the socket 15 extends only to or short of the plane of the center of rotation 16 of the ball 14 so that the joint can be readily disconnected by lifting the ball out of the socket when the holding means, to be described, is removed. This low socket also increases the angle of movement of the connector.

The suction nozzle is adapted to rotate in the operating plane around the axis 17 which extends through the center of rotation 16 and is perpendicular to the surface to be cleaned. The connector 11, however, is turnable in every direction around the center of rotation 16 to the extent determined by the position of a shoulder 14a which is adapted to engage the top of the socket 15 for limiting the movement of said connector. This shoulder may, however, be omitted in certain instances to provide a maximum angle of movement for the connector.

Inasmuch as all axes of rotation of the ball and socket joint pass through the center of rotation 16, it is desirable that the ball and socket be held together by spring pressure which is always directed toward this point. In the embodiment shown this is accomplished by providing a pin 18 which passes transversely through the ball 14 and is provided with an annular groove 19 located at the center of rotation 16. In the groove 19 there is supported the bent over end of a guide member 20 which extends in the direction of the axis 17 and is turnably supported as at 21 in a leaf spring 22 which bridges the lower suction opening of the suction nozzle 10 and may be attached thereto as by pins 22a. In this construction the leaf spring 22 remains stationary for all movements of the connector 11 for the reason that the guide member 20 is free to rotate about the axis 17 and the pin 18 turns about any desired axis passing through the point 16.

Although the spring 22 has been shown as arranged in the suction nozzle and adapted to apply spring pressure directly to the center of rotation 16 of the ball and socket joint, it is to be understood that the spring may, if desired, be positioned

either at the suction opening or at the pin 18 or at the guide member 20 or that any of the above mentioned elements may be spring mounted.

In the above described embodiment the arc of contact between the ball 14 and the socket 15 is reduced to a minimum inasmuch as this contact is not relied upon to hold the parts in assembled position. Consequently, the socket 15 can terminate at or short of the plane of the center of rotation 16 of the ball 14. The parts are resiliently held together by means of the spring 22 and guide member 20 above described. This arrangement is adapted to provide sufficient friction to prevent the suction nozzle from turning too freely and also provides sufficient resilience to prevent the joint from binding. It also assures an effective seal between the connector 11 and the suction nozzle 10. The nozzle is accordingly adapted to turn in all directions about an axis normal to the surface to be cleaned and may also turn with respect to the suction hose so as to accommodate various irregular surfaces, thereby providing a three dimensional mobility, that is freedom of the suction nozzle to turn about three axes which cross or intersect each other. The angle of movement about certain axes may be made greater than that about other axes by suitably positioning the shoulder 14a on the surface of the ball 14.

Figs. 5 and 6 illustrate an embodiment in which a greater arc of contact is obtained between the ball 14 and socket 15. In this embodiment a plate 24 is provided which extends beyond the socket 15 and increases the arc of contact with the ball 14. An annular groove 25 may be formed, partly in the plate 24 and partly in the housing of the suction nozzle 10, to receive one or both ends of the pin 18 so as to limit the tilting movement of the connector 40 without restricting the rotational movement thereof in a horizontal plane. The construction is otherwise similar to that described above in connection with Figs. 1 to 3.

Fig. 4 shows a different embodiment in which the pin 18 is provided with a transverse bore 26 adapted to receive a pin by which the guide

member 20 may be connected thereto. If desired the guide member 20 itself may be formed with an extension adapted to seat within the transverse bore 26. It is to be understood, however, that these details of construction may be modified in various ways without departing from the scope of the invention. If desired, the guide member 20 may be rigidly connected to the leaf spring 22 and may be turnably connected to the pin 18. Various other changes and modifications may be made as will be readily apparent to a person skilled in the art. 5 10 15

Although certain specific embodiments have been shown for purposes of illustration, it is to be understood that the invention is capable of various uses and is to be limited only in accordance with the following claims when interpreted in view of the prior art.

What I claim is:

1. A universal fluid-conveying joint for a suction nozzle having a surface engaging portion, a connector adapted to connect the same to a suction conduit, a freely rotatable and pivotal ball and socket joint interconnecting said suction nozzle and connector and having an aperture through which the suction air passes, spring means holding said ball and socket joint in assembled position, an annular channel formed in said suction nozzle in a plane parallel to said surface and means carried by said connector 20 and engaging said channel to limit the movement of said connector in certain directions. 25

2. In a universal fluid-conveying joint for a suction nozzle, a connector adapted to connect the same to a suction conduit, a freely rotatable and pivotal ball and socket joint interconnecting said suction nozzle and connector and having an aperture through which the suction air passes, a pin extending across the aperture in said ball and coinciding with a diameter of the ball, a link having a hooked end pivotally connected to the center of said pin, and a resilient bar extending across the aperture in said nozzle, said link being rotatably connected to the center of said bar.

GOSTA DAHL.
